DELIVERY ARRANGEMENT

James L. Blackley, Battle Creek, Mich., assignor,
by mesne assignments, to Goss Printing Press
Company, Chicago, Ill., a corporation of Illinois

Application September 8, 1944, Serial No. 553,270

14 Claims. (CL 271—75)

1

This invention is a novel variable speed delivery arrangement for delivering folded and printed newspapers of the like from a printing press, and the principal object of the invention is to provide an inexpensive, efficient, and practical means for variably controlling the continuous speed of the delivery belts by increments throughout a uniform range with relation to the speed of the folding cylinder of a printing press while the said press is in operation, as distinguished from varying the speed of the belts within each cycle only of the press, which cycles follow in repetition.

In the delivery of printed newspapers from a printing press folder there is, generally, but one speed for delivery of the papers in relation to the speed of the printing cylinder. As the speed of the printing cylinder increases to its maximum the delivery belt speed correspondingly increases. In modern high-speed printing presses this increase of delivery belt speed relative to the cylinder speed reaches a point where a multiplicity of pressmen or attendants must be employed in order to remove the papers from the delivery belts.

The alternative to this increase of pressmen or attendants is to operate the delivery belts at a much lower speed during capacity speed of the press. This alternative however is detrimental if for any reason the press has to be operated very much under its maximum capacity because the folded newspapers would then be crowded closer to the fly and may cause jamming thereof between the fly fingers and the delivery belts. In a number of newspaper organizations a more-or-less average page capacity prevails throughout the year, and consequently the proper relative delivery belt speed can be calculated to meet press attendant conditions. Other organizations, however, have fluctuating page capacity newspapers, ranging from single or fly-sheets to the maximum capacity paper, governed by the number of printing units of the press. In the former case, the papers could be stacked very much closer on the delivery belts than in the latter case.

My invention, therefore, is to provide a practical and novel means for controlling the speed of the delivery belts while the printing press is in operation, the delivery belts being driven directly from the press drive, whereby the speed of the delivery belts may be adjusted to accommodate the page capacity of the newspaper.

I will explain the invention with reference to the accompanying drawings which illustrate one practical embodiment thereof to enable others

2

familiar with the art to adopt and use the same; and will summarize in the claims, the novel features of construction, and novel combinations of parts, for which protection is desired.

- 5 In said drawings—
Fig. 1 is a side elevation of my novel variable speed delivery arrangement mounted in the frame of a printing press below the folding cylinder at the delivery end thereof.
10 Fig. 2 is a plan view, partially in section, showing the arrangement of this variable speed delivery in the press frame.
Fig. 3 is a vertical detail section on the line 3—3, Fig. 1.
15 As shown in Fig. 1, the printing press comprises side frames 1 having journaled therein, adjacent the delivery end, a folding cylinder 2 carrying on its end a gear 3 meshing with a gear 4 mounted on a shaft 5; said shaft 5 also carrying a bevel gear 6 meshing with a bevel gear 7 on the press folder drive shaft 8; the particular means for driving the folding cylinder 2 forming no part of my present invention.
20 Cooperating with folding cylinder 2 are a pair of folding rolls 9 and 10 journaled in the frame 1, the folded newspaper N being delivered by folding cylinder 2 between the folding rolls 9 and 10 into the fly fingers 11 carried by fly 12 mounted on a shaft 13 journaled in the side frame 1, the folded newspaper being delivered from the folding rolls 9 and 10 into the fly fingers 11 being illustrated in dot-and-dash lines in Fig. 1. A sheet stop 19 cooperates with the fly 12. Fly 12 carries a gear 14 meshing with a gear 15, journaled on a shaft 16 which also carries a gear 17 meshing with a gear 18 on the shaft 5 before mentioned, whereby the fly 12 is likewise driven by the press folder drive shaft 8. The particular means for driving the fly 12 however forms no part of my present invention.

- 25 Journalized in the press frames 1 below the shaft 13 is a shaft 20 having a worm gear 21 thereon meshing with a worm 22 on a vertical shaft 23 carrying at its upper end a bevel gear 24 meshing with a bevel gear 25 on the shaft 13; whereby shaft 20 is driven directly by and with the fly shaft 13 which latter shaft is driven from the press folder drive shaft 8, as above explained.

- 30 Worm gear 21 is preferably disposed at one end of shaft 20, as indicated in Fig. 2. At the opposite end of shaft 20 is a counting disk 26 of conventional type, and beyond disk 26 is a belt pulley 27 fixedly mounted on shaft 20 and disposed opposite a belt pulley 28 fixedly mounted 35 on a stub shaft 29 journaled in the adjacent

press frame 1; and a belt 30 runs around the pulleys 27 and 28 thereby driving shaft 29 by and with shaft 20 and in the same direction.

Shaft 29 carries a pulley 31 (Fig. 2) fixedly mounted thereon and disposed opposite a pulley assembly 32 of well known construction, the same being preferably but not necessarily constructed in accordance with United States Letters Patents Nos. 2,186,477 and 2,151,189, said pulley assembly 32 being mounted upon the vertical leg 33a of a bell-crank lever 33 pivoted as at 34 in the adjacent press frame 1. As shown the upper end of leg 33a of bell-crank lever 33 carries a horizontally disposed stub shaft 35 on which is mounted three belt cone members 32a, 32b, and 32c. Cone members 32a and 32c however maintain on shaft 35 their transverse relationship from one to the other while the central cone member 32b is free to approach towards or recede from either of the cone members 32a or 32c. The pulley formed by the cone members 32b and 32c is disposed opposite the pulley 31 on shaft 29, and a belt 36 runs around the said pulleys. The pulley formed by the cone members 32a and 32b is disposed opposite a pulley 37 fixedly mounted upon a sleeve 38 forming a pulley shaft freely journaled upon the shaft 20, as shown in Fig. 2, and a belt runs around the said pulleys.

By the above construction of the pulley assembly 32, as cone member 32b approaches cone member 32c the pitch line diameter of the belt 36 between the cone members 32b and 32c increases, and simultaneously the belt pitch line of the belt 39 between the cone members 32a and 32b decreases. An increase in the belt pitch line diameter between the members 32b and 32c shortens the center distance B, Fig. 2. While cone member 32b approaches member 32c, cone members 32a and 32b are separating so that belt pitch line diameter of the combination of 32a and 32b becomes smaller, and hence at the same time the center distance B is being shortened the center distance C (Fig. 2) is becoming greater. Thus any increase or decrease of the center distance B is compensated for by a correlative decrease or increase of the center distance C.

The separation and approach of the cone members 32a, 32b and 32c is governed by changing the position of the pulley assembly 32, to effect the shortening or lengthening of the center distance C and the corresponding shortening or lengthening of the center distance B. The particular means shown for accomplishing the above change in center distances B and C is as follows: The outer end of the horizontal leg 33b of bell-crank lever 33 carries a swivel stud 40 having a thread bore to receive an adjusting screw 41 pivoted on the press frame 1 through the instrumentality of a pivoting stud 41a free to rotate about its center. On screw 41 is a locknut 42 which retains the screw in adjusted relationship to the bell-crank lever 33. By the above arrangement any adjustment of adjusting screw 41 will cause the variable pulley assembly 32 which is carried by the bell-crank lever 33 to swing in an arc around pivot 34, and thereby change the center distances B and C.

Fixedly attached to sleeve or pulley shaft 38 are a number of delivery belt pulleys 43 (Fig. 2) which carry the belts 46 which convey the printed papers from the press, said belts 46 also running over a drum 47 and being preferably provided with adjustable tensioning pulleys 48 and 49, indicated in Fig. 1.

If it is desired to increase the continuous speed

of the delivery belts 46 in uniform ranges, adjusting screw 41 is rotated to swing bell-crank lever 33 in a counterclockwise direction about its pivot 34. The variable pulley assembly 32 will also move uniformly in a direction toward shaft 29 causing the center distance B to become greater and the center distance C to simultaneously become uniformly smaller. As center distance B uniformly increases the effective pitch line diameter of the pulley formed by the combination 32b, 32c becomes uniformly smaller, while the effective pitch line diameter of the pulley formed by the combination 32a, 32b becomes uniformly greater, and hence the ratio of the drive from pulley 31 to the pulley combinations 32b, 32c, and the drive from pulley combination 32a and 32b to pulley 37 has been uniformly changed, thereby speeding up the delivery belts 46, for continuous operation or movement. If it is desired to decrease the continuous speed of the delivery belts 46 in uniform ranges, the adjusting screw 41 is rotated to swing bell-crank lever 33 in a clockwise direction about its pivot 34.

The present types of deliveries have delivery pulleys rigidly attached to the shaft (such as 20) which receives its drive from an appropriate part of the folder, and consequently the delivery pulleys revolve at a definite speed with respect to the printing cylinders. In my construction the corresponding shaft 20 also revolves at a definite relative speed with respect to the printing cylinder which is desirable due to the fact that the counting disc 26 is mounted upon shaft 20 and thus rotates therewith at a predetermined ratio with respect to the printing cylinder. However, according to my invention when it is desired to increase or decrease the speed of the delivery belts 46 while the printing press is in operation, this may be effected without affecting the speed of the counting disc 26, by merely adjusting the screw 41, thereby changing the position of the pulley assembly 32 and altering the center distances B and C and the belt pitch line diameters of the cone members 32a, 32b and members 32b, 32c.

The construction shown discloses but one form of means for acquiring the desired results, but it is understood that the type of drive from pulley 27 to pulley 28 can be any convenient arrangement such as a chain drive or gear drive; also that the means for adjusting the pulley assembly 32 may be of any appropriate form to accommodate the particular shape of the machine to which arrangement is to be installed. I therefore do not limit my invention to the exact form shown in the drawings, for obviously changes may be made therein within the scope of the claims.

I claim:

1. In a counting and delivering machine having a driven rotatable folding cylinder delivering folded products to a fly; endless delivery belts cooperating with said fly and receiving in succession the folded products; means for continuously driving the belts from the folding cylinder drive and in step therewith, said delivery belt drive including means for adjusting it to operate at various uniform speeds with respect to that of the folding cylinder; said driving means including a shaft driven at a fixed speed ratio by the folding cylinder; a counting member operated by said shaft, said driving means including a second shaft parallel with and spaced from the first shaft and driven thereby; a pulley shaft over which one end of the belts run disposed

parallel with the second shaft; rotatable means over which the other end of the belts run; a lever pivotally mounted between said second and pulley shafts; a variable pulley assembly carried by said lever having outer cone members and a shiftable inner cone member forming a pair of variable belt pulleys whose pitch diameters vary inversely as the inner cone member is shifted towards or from an outer cone member; a pulley on the second shaft opposite one pulley of the pair of the variable assembly; a belt running around said pulley and the one pulley of said pair; a second pulley on the pulley shaft opposite the other variable pulley of the pair; a second belt running around said second pulley and other variable pulley; and means for shifting the said lever to change the pitch diameters of the pair of variable pulleys.

2. In a counting and delivering machine having a driven rotatable folding cylinder delivering folded products to a fly; endless delivery belts cooperating with said fly and receiving in succession the folded products; means for continuously driving the belts from the folding cylinder drive and in step therewith; means for varying the continuous speed of the delivery belts to operate at various uniform speeds with respect to the speed of rotation of the folding cylinder while the machine is in operation; said driving means including a shaft driven at a fixed speed ratio by the folding cylinder; a counting member operated by said shaft, said speed varying means comprising a second shaft parallel with and spaced from the first shaft and driven thereby; a pulley shaft over which one end of the belts run disposed parallel with the second shaft; rotatable means over which the other end of the belts run; a lever pivotally mounted between said second and pulley shafts; a variable pulley assembly carried by said lever having outer cone members and a shiftable inner cone member forming a pair of variable belt pulleys whose pitch diameters vary inversely as the inner cone member is shifted towards or from an outer cone member; a pulley on the second shaft opposite one pulley of the pair of the variable assembly; a belt running around said pulley and the one pulley of said pair; a second pulley on the pulley shaft opposite the other variable pulley of the pair; a second belt running around said second pulley and other variable pulley; and means for shifting the said lever to change the pitch diameters of the pair of variable pulleys.

3. In a machine having a driven rotatable folding cylinder delivering folded products to a fly; endless delivery belts cooperating with the fly and receiving in succession the folded products; means for driving the belts from the folding cylinder drive; and means for varying the speed of the delivery belts with respect to the speed of rotation of the cylinder while the machine is in operation; said driving means including a shaft driven at a fixed speed ratio by the cylinder; a sleeve freely journaled on said shaft having pulleys fixedly mounted thereon over which one end of the endless belts run; rotatable means over which the other end of the endless belts run; and said speed varying means connecting the shaft and sleeve.

4. In a machine as set forth in claim 3, said speed varying means comprising a second shaft parallel with and spaced from the first shaft and driven thereby; a lever pivotally mounted between said shafts; a variable pulley assembly carried by said lever having outer cone members

and a shiftable inner cone member forming a pair of variable belt pulleys whose pitch diameters vary inversely as the inner cone member is shifted towards or from an outer cone member; a pulley on the second shaft opposite one pulley of the pair of the variable assembly; a belt running around said pulley and the one pulley of said pair; a second pulley on the sleeve opposite the other variable pulley of the pair; a second belt running around said second pulley and other variable pulley; and means for shifting the said lever to change the pitch diameters of the pair of variable pulleys.

5. In a machine having a driven rotatable folding cylinder delivering folded products to a fly; endless delivery belts cooperating with the fly and receiving in succession the folded products; means for driving the belts from the folding cylinder drive; and means for varying the speed of the delivery belts with respect to the speed of rotation of the cylinder while the machine is in operation; said driving means including a shaft driven at a fixed speed ratio by the cylinder; a counting member operated by said shaft; a sleeve freely journaled on said shaft having pulleys fixedly mounted thereon over which one end of the endless belts run; rotatable means over which the other end of the endless belts run; and said speed varying means connecting the shaft and sleeve.

6. In a machine as set forth in claim 5, said speed varying means comprising a second shaft parallel with and spaced from the first shaft and driven thereby; a lever pivotally mounted between said shafts; a variable pulley assembly carried by said lever having outer cone members and a shiftable inner cone member forming a pair of variable belt pulleys whose pitch diameters vary inversely as the inner cone member is shifted towards or from an outer cone member; a pulley on the second shaft opposite one pulley of the pair of the variable assembly; a belt running around said pulley and the one pulley of said pair; a second pulley on the sleeve opposite the other variable pulley of the pair; a second belt running around said second pulley and other variable pulley; and means for shifting the said lever to change the pitch diameters of the pair of variable pulleys.

7. In a delivery arrangement for receiving in succession folded products, endless delivery belts; a shaft driven at relatively constant speed; a sleeve freely journaled on said shaft having pulleys fixedly mounted thereon over which one end of the endless belts run; rotatable means over which the other end of the endless belts run; a second shaft parallel with and spaced from the first shaft and driven thereby; a lever pivotally mounted between said shafts; a variable pulley assembly carried by said lever having outer cone members and a shiftable inner cone member forming a pair of variable belt pulleys whose pitch diameters vary inversely as the inner cone member is shifted towards or from an outer cone member; a pulley on the second shaft opposite one pulley of the pair of the variable assembly; a belt running around said pulley and the one pulley of said pair; a second pulley on the sleeve opposite the other variable pulley of the pair; a second belt running around said second pulley and other variable pulley; and means for shifting the said lever to change the pitch diameters of the pair of variable pulleys to vary the speed of the belts with respect to the speed of the first shaft.

8. In a delivery arrangement as set forth in claim 7, said lever comprising a bell-crank lever, one leg of which carries the variable pulley assembly, and the other leg is engaged by the shifting means.

9. In a delivery arrangement as set forth in claim 7, said lever comprising a bell-crank lever one leg of which carries the variable pulley assembly; and said shifting means comprising a nut pivotally carried by the other leg of the lever, and a pivoted bolt engaging the said nut whereby rotation of the bolt will shift the lever.

10. In a delivery arrangement as set forth in claim 7, a counting member operated by the first shaft, whereby the counting will be unaffected by variations in the speed of the belts.

11. In a machine having a driven rotatable folding cylinder delivering folded products to a fly; endless delivery belts cooperating with the fly and receiving in succession the folded products; means for driving the belts from the folding cylinder drive, and means for varying the speed of the delivery belts with respect to the speed of rotation of the folding cylinder while the machine is in operation, said driving means including a shaft driven at a fixed speed ratio by the folding cylinder drive; a rotatable member mounted on a second shaft freely journaled on said first shaft and over which one end of the endless belts run; a second rotatable member over which the other end of the endless belts run; one of said rotatable members driving the belts; and said speed varying means connecting the first shaft and the said driving rotatable member for driving said belts.

12. In a machine as set forth in claim 11, said speed varying means comprising a second shaft parallel with and spaced from the first shaft and driven thereby; a lever pivotally mounted between said shafts; a variable pulley assembly carried by said lever having outer cone members and a shiftable inner cone member forming a pair of variable belt pulleys whose pitch diameters vary inversely as the inner cone member is shifted towards or from an outer cone member; a pulley on the second shaft opposite one pulley of the pair of the variable assembly; a belt around said pulley and the one pulley of said pair; a second pulley on rotatable member on the first shaft, said pulley being disposed opposite the other variable pulley of the pair; a second belt running around said second pulley and other variable pulley; and means for shifting said lever to change the pitch diameters of the pair of variable pulleys.

13. In a machine having a driven rotatable folding cylinder delivering folded products to a

5 fly; endless delivery belts cooperating with the fly and receiving in succession the folded products; means for driving the belts from the folding cylinder drive; and means for varying the speed of the delivery belts with respect to the speed of rotation of the folding cylinder while the machine is in operation; said driving means including a shaft driven at a fixed speed ratio by the folding cylinder drive, a rotatable means 10 over which one end of said endless belts run; a second rotatable means over which the other end of the endless belts run; and a drive pulley connected to said endless belts for movement in fixed relation thereto; said speed varying means 15 connecting said drive pulley to said first shaft.

14. In a machine having a driven rotatable folding cylinder delivering folded products to a fly; endless delivery belts cooperating with the fly and receiving in succession the folded products; means for driving the belts from the folding cylinder drive; and means for varying the speed of the delivery belts with respect to the speed of rotation of the folding cylinder while the machine is in operation; said driving means 20 including a shaft driven at a fixed speed ratio by the folding cylinder, rotatable means over which one end of said endless belts run; said rotatable means being concentrically mounted on and adapted to rotate at varying speeds relative to 25 said first shaft; a second rotatable means over which the other end of the endless belts run; and a drive pulley connected to said endless belts for movement in fixed relation thereto; said speed varying means connecting said drive pulley to said first shaft.
